Patented Dec. 23, 1919.

Inventor:
Raymond T. Ashley

UNITED STATES PATENT OFFICE.

RAYMOND T. ASHLEY, OF RENO, NEVADA.

ROTARY MOTOR.

1,325,684.

Specification of Letters Patent. Patented Dec. 23, 1919.

Application filed May 15, 1918. Serial No. 234,818.

To all whom it may concern:

Be it known that I, RAYMOND T. ASHLEY, a citizen of the United States, and a resident of the city of Reno, county of Washoe, and 5 State of Nevada, have made a new and useful Invention—to wit, Improvements in Rotary Motors; and I do hereby declare the following to be a full, clear, concise, and exact description of the same.

10 The present invention relates particularly to internal combustion rotary motors.

The objects of this invention are to produce a motor of this type, simple in construction and so combined and arranged that 15 intake and compression are accomplished simultaneously by the same piston. Other objects and advantages will appear as this description progresses.

Referring to the drawing which forms a 20 part of this specification and appended claims;

Figure 1 is an end view of the motor partly broken away to show certain parts.

Fig. 2 is a view partly in side elevation 25 partly in longitudinal section and partly broken away to show certain parts.

Fig. 3 is a view of the exhaust.

Fig. 4 is a fragmentary view of the cylinder-carriers.

30 In detail the construction illustrated in the drawings includes the stator 1 mounted upon a suitable base 2. The stator comprises a casing for the operative parts, its internal periphery being circular. To the 35 opposite sides of the stator annular heads 3 and 4 are bolted to the flanges 5—5 formed on the stator.

A motor shaft 6 extends co-axially 40 through the stator and through heads 3 and 4 and is journaled in bearings 7 and 8 mounted on said covers respectively in spiders 9 formed on said covers. A rotor 10 is keyed on shaft 6 within the stator 1. The rotor comprises an intermediate hollow casting 11, formed with a central hub 12 through which the shaft 6 extends, spokes 13 radiating from said hub, a peripheral rim 14 joined to the extremities of said spokes, and a pair of plates 14' and 15 secured to the 45 sides of casting 11 and formed with hubs 16 through which shaft 6 extends which hubs are keyed to said shaft. The periphery of the rotor rim 14 is formed with concentric arcs 17 which approximate packing contact 50 with the internal periphery of the stator, and with eccentric portions 18 which extend

inwardly from the internal periphery of the stator forming combustion chambers 19 between the stator peripheral wall and said eccentric rim portions, and forming rotor 60 pistons 18' which are acted upon by the expansion of gas in said combustion chambers, to rotate said rotor.

One or more planetary cylinder-carriers 20 are rotatably journaled in the rotor entirely eccentric to the rotor shaft and approximately internally tangent to the arcuate portions 17 of the rotor and each of said cylinder-carriers carries a diametrical cylinder 21 open at its ends. The cylinder-carriers are provided with elongated interchangeable inlet-or-outlet ports 22 communicating with the open ends of the cylinders 21, said ports being elongated substantially parallel to the shaft 6. The rotor 75 shaft is provided with a fuel conduit 23 which communicates with the source of fuel supply, and is also provided with an axially elongated port 24 leading from said conduit and adapted to register with one of the 80 cylinder-carrier ports 22 when the cylinder of the carrier extends radially to the rotor shaft, thus admitting fuel into the cylinder. Outlet ports 25 are provided in the arcuate portions 17 of the rotor rim, with which one 85 of the cylinder-carrier inlet-or-outlet ports 22 registers when the cylinder of the carriers extends radially to the rotor shaft. The outlet ports 25 are equal in width to the carrier ports 22 but are not elongated. The 90 cylinder-carriers 20 are journaled in the rotor by means of axial trunnions 26 extending outwardly from the carriers and bearings 27 in the rotor plates 14 and 15 in which bearings the trunnions are journaled. 95 The reciprocating pistons 28 are mounted in the cylinders 21, the ends of the pistons conforming to the arc of the carriers 20 extending over the ends of the cylinders. An intermittent movement 30 is provided for 100 intermittently rotating the carriers 20 and cylinders 21 in half revolutionary increments to establish and shut off communication between the inlet-or-outlet ports 22 and the inlet ports 24 and outlet ports 25 to admit gas into one end of the cylinders 21 and to allow the escape of gas from the other end thereof. The intermittent movement 30, preferably a Geneva movement, includes star members 31 and a co-acting member 32. 110 The star members are secured to the outer ends of studs 33 which are secured to the

cylinders 21 and extend through and are keyed to the trunnions 26 of the carriers 20. The star-coacting member is secured to the spider 9 of the head 3 and has a cylindrical periphery broken at suitable points coacting with the concaved surfaces of the star members. The star-coacting member 32 has an annular flange in which pins 34 are slidably mounted, said pins being adapted to enter the radial slots 35 of the star member 31 to rotate the cylinder carriers and cylinders intermittently as the rotor is rotated. An annular handle 36 is connected to the outer ends of the pins 34 and is slidably mounted on the spider 9 of head 3 by means of which handle the pins are moved into and out of the path of movement of the slotted points of the star wheel 31. The stator is formed with a by-pass 40 into which the gas 20 discharges from the cylinders 21 through the carrier ports 22 and rotor port 25. A spark plug 41 secured in the stator extends into the by-pass 40 for igniting the gas therein. A seal 50 composed of a plurality 25 of independent laminations, superimposed one behind the other in the direction opposite to the direction of rotation of the rotor, is slidably mounted in a tubular bearing 51 on the stator 1 which seal projects through 30 and is maintained in engagement with the periphery of the rotor by means of weights 52 resting on top of the seal, said seal serving to prevent back action of the expanding gas and as a gas reaction area or cross-head 35 to direct the force of the expanding gas against the rotor piston 18. An oil cup 53 is mounted on top of the tubular extension 51 for oiling the seal. The stator is formed with an exhaust 55 having a pair of ports 40 56 out of registration with the rotor port 25, a wall 57 being interposed between said ports in alignment with the rotor port for maintaining said rotor port closed as the rotor passes the exhaust.

45 The particular construction and mounting of the cylinder-carriers are such that the cylinders and carriers may be readily assembled and mounted in the rotor or taken apart and removed for repairs. The carriers comprise a cylindrical shell 60, a casting 61 contained within said shell and a pair of disks 62 and 64 engaging the ends of said shell and secured to the ends of casting 61 by screws 63. The shell 60 is secured 50 to the cylinder casting 61 by screws 64. The carriers fit within cylindrical receptacles 65 formed in the rotor and extending longitudinally through the intermediate rotor casting 11, the periphery of the carrier shells 60 resting in sealing contact with the inner surface of the receptacle walls, thus preventing escape of gas from the cylinders through ports 22 when the carrier is rotated and said ports are out of registration with 55 rotor port 25. The carriers are maintained

properly in position within the rotor receptacles by the engagement of rotor and plates 15 and 16 with the carrier end disks 62 and 63. The carriers may be removed or introduced into the carrier receptacles 65 when 70 one of the rotor end plates 15 or 16 is removed. The cylinders 21 may be removed from the carriers by unscrewing the disks 62 and 63 and the shells 60 from the cylinder castings and by unscrewing and then 75 withdrawing the cylinder castings longitudinally from the shells.

This invention operates substantially as follows:

Referring to Fig. 1, the driven shaft 6 is 80 given an impulse by the usual method in a clockwise direction, the pins 34 of the intermittent movement 30 being withdrawn so that cylinder-carriers 20 are free to revolve with the rotor without revolving in their 85 own bearings 27, thus avoiding undue friction on starting. As speed is attained, the throttle is opened and the pins 34 pushed into the path of the star wheels of the intermittent movement, so as to cause the 90 intermittent movement to operate. Cylinder-carriers revolve so as to place cylinders in radial position, the piston 28 being held in its position by reason of vacuum behind it and as the cylinder reaches its radial position, inlet port 22 becomes coincident with 95 inlet port 24, the piston immediately by centrifugal action moves radially outward with constantly accelerating velocity as its radial distance from shaft 6 of rotor increases thus 100 filling cylinder behind it with combustible fuel mixture. Intermittent movement operates again during the succeeding revolution of the rotor, causing cylinder-carrier to revolve one half revolution. Thus cylinder 105 21 again reaches radial position, the piston 28 again being at inner end of the cylinder, with full charge of fuel between it and the periphery of rotor at arc 17. The piston again moves radially outward, intaking another charge exactly as before and compressing the charge already ahead of it, the rotor and stator being in packing contact throughout arc 17, thereby sealing against escape of 110 gas. As the arc 17 passes the rear end of 115 by-pass 40 coincident ports 22 and 25 allow the compressed mixture to escape and flow back so as to fill combustion chamber 19 at the rear end of the arc, the forward portion of the arc closing the by-pass to the combustion space in advance of the arc. As the piston reaches its maximum radial distance, thus scavenging all fuel-mixture from the cylinder, the coincident ports 22 and 25 pass the forward end of the by-pass 40 and rotor 120 and stator again become in packing contact. Immediately a spark is passed to spark plug 41, situated in by-pass 40. The burning fuel in expanding against the portion 18 of the 125 rotor acting as firing-piston forces the rotor 130

to revolve until the burned gases have reached the maximum capacity of the firing cycle, the seal 50 acting as reaction-area or "cross-head". As rotation progresses, the 5 dead gas is allowed to escape through exhaust 55 and is scavenged by the approach of the succeeding close contact between the rotor and stator. The gas in burning expands through a cycle represented by the peripheral distance between the point or separated peripheral points 17-17 however numerous these may be.

The cycle of operation may be accomplished as many times per revolution as 15 there are carriers internally revolving within said rotor in the synchronized and symmetrical relation here shown.

In this specification and the annexed drawing I have disclosed my invention in a desirable form, but I do not limit my invention to such form because it may be embodied in other forms, and it is to be understood that in and by the claims following the description herein I intend to cover my invention in 20 whatever form it may be embodied.

What I claim and desire to secure by Letters Patent is:

1. A rotary motor comprising a stator, a rotor mounted in said stator, a planetary cylinder mounted to revolve with said rotor and to revolve independently of said rotor; a piston in said cylinder operable by centrifugal force; a portion of the periphery of said rotor and a portion of the wall of said 35 stator forming a combustion chamber, a firing-piston on said portion of said rotor periphery, means for introducing fuel mixture into said cylinder and compressing said fuel in the cylinder by the centrifugal force exerted by said first mentioned piston; means for allowing the compressed fuel to escape from the cylinder into said combustion chamber; means for igniting said fuel in said chamber; means for receiving the reaction of the combustion, and means for exhausting said chamber.

2. A rotary motor comprising a stator, a rotor mounted in said stator, said rotor approximating sealing contact with the internal periphery of the stator through an arcuate portion thereof; a portion of the periphery of the rotor elsewhere deviating to form a combustion space, a firing-piston on said peripheral portion of the rotor, a seal extending across said combustion space into contact with the periphery of the rotor to form a reaction-area in the rear of said piston; means in said rotor for receiving fuel mixture; means for introducing fuel mixture into said receiving means, said stator being provided with a by-pass in advance of said seal, said rotor being provided with an outlet port in advance of said combustion space for discharging the fuel mixture in said rotor through said by-pass into

said combustion space; means for igniting said fuel mixture, and means for exhausting said combustion space.

3. A rotary motor comprising a stator, a rotor mounted in said stator, said rotor approximating sealing contact with the internal periphery of said stator through an arcuate portion thereof, a portion of the periphery of the rotor elsewhere deviating to form a combustion space; a firing-piston on 70 said peripheral portion of the rotor; a seal extending across said combustion space into contact with the periphery of said rotor and adapted to form a reaction-area in the rear of said piston; means in said rotor for receiving fuel mixture and compressing said mixture by centrifugal force, said stator being provided with a by-pass in advance of said seal, said rotor being provided with an outlet port in advance of said combustion 75 space for discharging the fuel mixture in said rotor through said by-pass into said combustion space; means for igniting said fuel mixture and means for exhausting said combustion space.

4. A rotary motor comprising a stator, a rotor mounted in said stator, a plurality of arcs of the periphery said rotor approximating sealing contact with the internal periphery of said stator, the said rotor elsewhere deviating between said peripheral arcs and forming a plurality of combustion spaces with the peripheral wall of the stator; a firing-piston on each of said peripheral deviations; a seal extending across said 85 combustion spaces into contact with said rotor and adapted to form a reaction-area in the rear of said firing-piston; means in said rotor for receiving fuel mixture, means for introducing fuel mixture into said receiving 90 means, said stator being provided with a by-pass in advance of said seal, said rotor being provided with outlet ports through said peripheral arcs for discharging fuel mixture through said by-pass successively 100 into each combustion space at the rear of each outlet port; means for igniting the charge in each combustion space, the forward part of each arc closing the forward end of said by-pass while the port in the 105 arc discharges through said by-pass into said combustion chamber; and means for exhausting the products of combustion from said combustion spaces.

5. A rotary motor comprising a stator, a 120 rotor mounted in said stator, an arc of the periphery of said rotor approximating sealing contact with the internal periphery of said stator, the periphery of the rotor deviating from said arc away from the stator 125 wall and then approximating sealing contact with the internal periphery of the stator and forming with the stator wall a combustion chamber, a planetary cylinder mounted in said rotor, a piston in said cylinder; 130

means for rotating said cylinder to bring it into functioning radial position; means for introducing fuel into the inner end of said cylinder when the cylinder is in said radial position, said piston moving outward under the influence of centrifugal action simultaneously to intake fuel into the inner end of the cylinder and to compress fuel in its outer end, said rotor being provided with 10 an outlet port to discharge the compressed fuel into said combustion chamber, a seal extending across said combustion space into contact with the rotor, said stator being provided with a by-pass in advance of said 15 seal; means for igniting the fuel in said combustion chamber, and means for exhausting said combustion chamber.

6. A rotary motor comprising a stator, a rotor mounted in said stator, a plurality of 20 arcs of said rotor approximating sealing contact with the internal periphery of said stator, the periphery of said rotor deviating between said peripheral arcs and forming, with the wall of the stator, a plurality of 25 combustion spaces, a firing-piston on each of said peripheral deviations, a plurality of planetary cylinders mounted in said rotor; a piston in each of said cylinders; means for rotating said cylinders to bring them 30 into functioning radial position; means for introducing fuel into the inner end of said cylinders when said cylinders are in functioning radial position, said pistons moving outward under centrifugal action and simultaneously 35 intaking fuel into the inner end of the cylinders and compressing the fuel in the outer end of the cylinders; said rotor being provided with a plurality of outlet ports adapted respectively to communicate with 40 the outer end of said cylinders when in functioning radial position to successively discharge the compressed fuel from said cylinders respectively and successively into said combustion chambers; a seal extending 45 across said combustion space into contact with the rotor said stator being provided with a by-pass in advance of said seal; means for successively igniting said fuel in said combustion chambers, and means for 50 exhausting said combustion chambers.

7. A rotary motor comprising a stator, a rotor mounted in said stator, an arc of the periphery of said stator approximating sealing contact with the internal periphery of 55 said stator elsewhere deviating to form, a combustion chamber, said rotor being provided with a cylindrical receptacle, a planetary cylinder carrier turnably fitting in said

receptacle in sealing contact with said receptacle wall, a cylinder carried by said carrier, and rotatable with the carrier, a pair of interchangeable inlet and exhaust ports in said carrier communicating respectively with the ends of said cylinder, said receptacle being provided with an inlet and exhaust port, 60 with which said carrier ports alternately register during rotation of the carrier, means for rotating said cylinder carrier to bring said carrier ports alternately in registration with said receptacle inlet and exhaust ports; 70 means for introducing fuel mixture through said receptacle inlet port and the cylinder port in registration therewith when the cylinder is in functioning radial position; a piston in said cylinder adapted to move outward 75 from the axis of the rotor under the action of centrifugal force when the cylinder is in functioning radial position simultaneously to intake fuel through said receptacle inlet and registering carrier port into the inner 80 end of the cylinder and to compress fuel previously introduced in the outer end of the cylinder; means for enabling the compressed fuel to discharge through the port in the outer end of the cylinder and the receptacle 85 outlet port into said combustion chamber; means for igniting said fuel in said combustion chamber; means for receiving the reaction from the combustion, and means for exhausting the products of combustion from 90 said combustion chamber.

8. A rotary motor comprising a stator, a rotor mounted in said stator, an arc of the periphery of the rotor approximating sealing contact with the internal periphery of 95 said stator through an arcuate portion thereof elsewhere deviating and forming a combustion chamber with the stator wall, a piston on said periphery deviation; a fuel receiving and discharging device in said 100 rotor; means for introducing fuel into said device when in fuel receiving position; means for enabling said device to discharge the fuel therefrom into said combustion chamber, an intermittent movement for intermittently moving said device into receiving and discharging position; means for igniting said fuel in said combustion chamber; 105 means for receiving reaction from combustion; means for exhausting said chamber, 110 and means for rendering said intermittent movement inoperative.
